UNITED STATES PATENT OFFICE.

JOSEPH O. ARDUSER, OF KOKOMO, INDIANA, ASSIGNOR TO D. C. JENKINS GLASS COMPANY, OF KOKOMO, INDIANA, A CORPORATION.

DESIGN FOR A TUMBLER.

Application filed April 20, 1929. Serial No. 30,952. Term of patent 3½ years.

To all whom it may concern:

Be it known that I, JOSEPH O. ARDUSER, a citizen of the United States, residing at the city of Kokomo, county of Howard, and State of Indiana, have invented a new, original, and ornamental Design for Tumbler, of which the following is a specification, reference being had to the accompanying drawing, forming part thereof.

In the drawings, Fig. 1 is a side elevation of a tumbler, showing my new design; and Fig. 2 is a top plan view thereof.

I claim:

JOSEPH O. ARDUSER.
